UNITED STATES PATENT OFFICE.

HARRY W. STIMSON, OF WEST ALLIS, WISCONSIN.

LAPPING-IN TOOL FOR INTERNAL-COMBUSTION ENGINES.

Application filed October 2, 1922. Serial No. 591,893.

To all whom it may concern:

Be it known that I, HARRY W. STIMSON, a citizen of the United States, and resident of West Allis, in the county of Milwaukee and State of Wisconsin, have invented new and useful Improvements in Lapping-In Tools for Internal-Combustion Engines, of which the following is a description, reference being had to the accompanying drawings, which are a part of this specification.

This invention relates to a lapping-in tool for internal combustion engines. Tools of this character are used for grinding and polishing the inner surfaces of a cylinder so that the piston will fit properly.

It is an object of this invention to provide a structure of this type wherein the lapping tools may be quickly and easily adjusted and readily secured in their adjusted positions.

A lapping-in tool constructed in accordance with this invention has also the added advantages that slight adjustments may be made with facility and the lapping tools easily released so that the device may be withdrawn from the cylinder.

The invention further consists in the novel combination, construction and arrangement of parts wherein the objects of this invention are efficiently accomplished. The invention will be described in detail in the accompanying specification when considered with the accompanying drawings wherein:

Figure 1 is an elevational sectional view through a lapping-in tool constructed in accordance with this invention; and,

Fig. 2 is a sectional view, partly broken away, taken on the plane indicated by the line 2—2 in Fig. 1.

Referring now more particularly to the drawings wherein like reference characters indicate like parts, it will be noted that the device consists essentially of a shaft 10 provided at one end thereof with a collar member 11 to which there is pivotally secured a plurality of link members 12. Pivotally secured to each link member, as at 13, is a lapping tool 14, a plurality of these lapping tools being employed, as clearly illustrated in Fig. 2.

Displaceable longitudinally of the shaft 10 is a bevelled collar 15, the bevelled surface 16 of which is adapted to engage the inner ends 17 of the link members 12 so that as the collar 15 is moved toward the inner end

of the shaft 10, the lapping tools 14 will be expanded outwardly to increase the diameter of the lapping tool.

The collar 15 is operated by means of a sleeve 18 which surrounds the shaft 10 and is rigidly connected to the bevelled collar 15 at one end, and is provided at its outer end with a plurality of spring actuated dogs 19, pivoted thereto as at 20. Each dog 19 is provided at one end with a plurality of saw teeth 21, which in turn are adapted to engage with a threaded portion of a sleeve 22 mounted on the shaft 10. The abrupt faces of the saw teeth 21 are so disposed that accidental movement of the sleeve 18, and consequently of the bevelled member 15, away from the lapping tools 14 is prevented but adjustment of the bevelled member 15 toward the lapping tools is permitted.

Loosely surrounding the sleeve 18 is a collar 23 provided on one of its edges with a bevelled recess 24 adapted to engage the bevelled ends 25 of the dogs 19. Obviously by displacing the collar 23 toward the dogs 19, the engagement of the bevelled surfaces 24 and 25 will lift the saw teeth 21 of each dog from engagement with the threads of the sleeve 22, whereupon the sleeve 18, together with the bevelled collar 15 may be readily moved along the shaft 10. This arrangement is provided so that a large adjustment may be quickly made, or pressure upon the lapping tools 14 immediately relieved, so that the tool may be withdrawn from the interior of the cylinder.

Mounted also on the shaft 10 is a sleeve 26, this sleeve being prevented from longitudinal displacement relative to the shaft 10 by means of two collars, 27 and 28, both fixed to the shaft 10. This sleeve 26 has a threaded engagement with the sleeve 22 so that by rotating this sleeve, the bevelled collar 15 may be adjusted longitudinally to adjust the tension of the spring 29.

The coiled spring 29 which yieldingly holds the parts in adjusted positions is disposed within the sleeve 18. A guide plate 30, fits loosely on the shaft 10 and acts as a stop to gauge the distance the tool is fed in the cylinder. A collar 31 fixed on the shaft 10, supports the tool with respect to the plate. Obviously, any suitable means may be provided for rotating the shaft 10 during the use of the tool. It is understood that in lapping the cylinder, the lapping

members 14 are provided with a lapping compound which is in the nature of an abrading material. It is further understood that the lapping members 14 can be charged with an abrasive thereby eliminating lapping compounds.

From the foregoing it will be immediately apparent that there is herewith described and illustrated a lapping-in tool which may 10 be quickly and easily adjusted to the desired size, and which is furthermore capable of minute adjustments. Means are provided for maintaining the parts in their adjusted positions and of quickly releasing the lapping members so that the tool may be withdrawn from the interior of the cylinder.

The arrangement of the parts is such that a tool constructed in accordance with this 20 invention may be cheaply and durably manufactured and liability of the same becoming broken is reduced to a minimum.

While one specific embodiment of the invention is described and illustrated herein, it is not intended that this invention 25 be unnecessarily limited, but reservation is made to make such changes and modifications as may come within the purview of the accompanying claims.

Having thus described the invention what 30 is claimed is:

Claims:

1. In a tool of the class described, a plurality of lapping members, axially displaceable means including releasable dogs for 35 radially displacing said members and means for releasing said dogs.

2. In a lapping-in tool for internal combustion engines, a plurality of pivoted lapping members, a shaft carrying said members, a collar provided with a bevelled surface for radially displacing said lapping members, means for displacing said collar and releasable means for locking said collar in its adjusted position.

45 3. In a lapping-in tool for internal combustion engines, a shaft adapted to be rotated, a plurality of lapping members pivotally supported upon said shaft, a collar longitudinally displaceable of said shaft and adapted to engage said lapping members for 50 displacing the same radially, means including a plurality of dogs for adjusting said collar and for securing said collar in its adjusted position and means for releasing said dogs.

55 4. In a lapping-in tool for internal combustion engines, a shaft adapted to be rotated, a plurality of lapping-in members pivotally mounted on said shaft, a collar mounted on said shaft and longitudinally displaceable relative thereto, said collar being adapted to displace said lapping members, means embodying a plurality of spring actuated dogs for displacing said collar and 60 for securing said collar in its adjusted position and additional means for providing limited adjustment of said collar.

5. In a lapping-in tool for internal combustion engines, a shaft adapted to be rotated, a plurality of lapping-in members 70 pivotally mounted on said shaft, a collar mounted on said shaft and longitudinally displaceable relative thereto, said collar being adapted to displace said lapping members, means embodying a plurality of spring 75 actuated dogs for displacing said collar and for securing said collar in its adjusted position, additional means for providing limited adjustment of said collar and means for simultaneously releasing said spring dogs. 80

6. In a lapping-in tool of the class described, a shaft, a plurality of lapping members, links for pivotally securing said lapping members to said shaft, a sleeve longitudinally displaceable along said shaft, 85 a collar provided with a bevelled surface secured to said sleeve at one end thereof and adapted to engage said links for radially displacing said lapping members, a plurality of spring actuated dogs mounted on 90 the other end of said sleeve and a second sleeve mounted on said shaft and provided with threads adapted to be engaged by said dogs whereby said bevelled collar may be freely moved in the direction in which 95 it radially displaces said lapping members.

7. In a lapping-in tool of the class described, a shaft, a plurality of lapping members, links for pivotally securing said lapping members to said shaft, a sleeve longitudinally displaceable along said shaft, a collar provided with a bevelled surface secured to said sleeve at one end thereof and adapted to engage said links for radially displacing said lapping members, a plurality of spring actuated dogs mounted on 100 the other end of said sleeve, a second sleeve provided with a threaded portion mounted on said shaft, said dogs being provided with saw teeth for engagement with said threaded portion whereby said first mentioned sleeve and collar may be freely moved in one direction and means engaging said second sleeve for further longitudinally adjusting 105 said collar.

8. In a lapping-in tool of the class described, a shaft, a plurality of lapping members, links for pivotally securing said lapping members to said shaft, a sleeve longitudinally displaceable along said shaft, a collar provided with a bevelled surface secured to said sleeve at one end thereof and adapted to engage said links for radially displacing said lapping members, a plurality of spring actuated dogs mounted on 110 the other end of said sleeve, a second sleeve provided with a threaded portion mounted on said shaft, said dogs being provided with saw teeth for engagement with said threaded portion whereby said first men- 115

tioned sleeve and collar may be freely removed in one direction and means for simultaneously releasing said dogs.

9. In a lapping-in tool for internal combustion engines, a rotatable shaft, a plurality of lapping-in members secured to said shaft, means for radially adjusting said lapping-in members, a guide plate for said rotatable shaft and a stop carried by said shaft and adapted to engage said plate to limit the movement of said tool into the engine cylinder.

10. The combination with a lapping-in

tool of the class described including a rotatable shaft adapted to be inserted into the cylinder of an engine of a guide plate engaging the open end of the cylinder being ground for guidingly supporting said shaft and a stop adjustably secured to said shaft and engaging said plate for limiting the extent to which said tool may be inserted into the cylinder.

In testimony whereof, I affix my signature.

HARRY W. STIMSON.
